UNITED STATES PATENT OFFICE

HARRY S. WILLIAMS, OF DENVER, COLORADO, ASSIGNOR TO WILLIAM A. BRYANS, OF DENVER, COLORADO

COLLAPSIBLE FOUNTAIN SYRINGE

Application filed May 10, 1930. Serial No. 451,270.

My invention relates to water bags and more particularly to collapsible fountain syringes, and has for its principal objects to reduce the proportionate amount of space required for packing a collapsed bag, to adapt a rubber bag of the bellows type for use as a reservoir of a fountain syringe.

Further objects of the invention are to provide a collapsible fountain syringe or water bag of bellows type, having a circular bottom provided with a central threaded nipple to which the usual rubber tube having a suitable nozzle, may be coupled; a flat ring being secured by vulcanization to the top of the bag, and connected to the bottom by flexible connections which limit the extension of the bag when the same is filled with water, the said flat ring having a hinged supporting bail.

20 I accomplish these objects by the character of bag or syringe illustrated in the accompanying drawing, in which

Fig. 1 is a perspective view of my improved collapsible fountain syringe suspended from a wall hook, a conducting tube being shown fragmentarily, and walls of the bag being partly broken away to better illustrate construction.

Fig. 2 is a perspective view of the device 30 in collapsed position.

Fig. 3 is a perspective view of a container illustrating the collapsed syringe and tube packed therein, the container wall being partly broken away for better illustration.

25 Referring to the accompanying drawing, the numeral 1 designates the bag proper, which is preferably made of rubber, and which is constructed to be folded or collapsed bellows fashion, after the manner of a 40 Chinese lantern.

To the lower edge of the bag is a bottom 2 having a central hole 3, in which is secured a flanged internally threaded nipple 4. To the top edge portion of the bag is secured a 45 thin flat metal ring 5 by vulcanization, and the ring is connected to the bottom plate by a pair of flexible connections, preferably chains 6, which prevent excessive extension of the bag. A pair of apertured lugs 7 are 50 secured to the ring 5 in which are inserted

the bent ends of a bail 8, by which the bag or syringe may be suspended when in use.

To the nipple 4 is adapted to be secured a tube or hose 9, of the character usually employed in connection with the common type 55 of water bag, the tube being provided at one end with a threaded coupling member 10, which is screwed in the nipple as shown in Fig. 1. The other end of the tube is adapted to receive any desired form of nozzle, not 60 shown.

A fountain syringe of this character may be only four inches in diameter, and when collapsed will occupy a space of less than a half inch in depth, so that it may be placed 65 in a hollow case in which the tube 9, after being disconnected from the bottom plate, may also be placed in coiled form, and the case will occupy but a small space, and may therefore be conveniently carried either on the 70 person or in a suit case or hand bag when travelling.

In practice, the bag is suspended from a hook by means of the bail 8 and will extend by gravity to the limit defined by the chains 75 6; the tube 9 is then connected to the nipple 4, and the bag is filled with water, and is then ready for use. As the bag has a relatively large opening through the ring 5, it may be easily filled with water, and after use may 80 be easily and quickly dried out before being collapsed, and placed in a case, thereby preserving the life of the rubber. While I have specifically referred to use of the bag as a collapsible fountain syringe, its adaptability 85 for use as a water bottle or ice pack is apparent.

What I claim and desire to secure by Letters Patent is:

1. A device of the character described comprising a circular bellow-like collapsible bag of water proof material, a bottom for the bag having an outlet nipple for connection thereto of a water tube, a flat metal ring secured to the top of said bag by vulcanization, a hinged bail secured to said ring at opposite diametric points, and flexible members connecting said ring and said bottom for limiting the extension of the bag.

2. A device of the character described

comprising a bellow-like collapsible bag having an outlet nipple, a flat ring secured to the top of the bag by vulcanization, a hinged bail on the ring, and flexible members

5 extending longitudinally within the bag for connecting said ring and the bottom of the bag to prevent excessive extension of the bag.

3. A device of the character described including a bellows bag formed of pliable material, a reenforcing member forming the top of the bag, means connected with the reenforcing member for suspending the bag and flexible means connecting the bottom of the bag with the reenforcing member for

10 limiting extension of the bag.

4. A device of the character described comprising a bellows-like collapsible bag of water proof material, a bottom for the bag having an outlet nipple, a metal ring secured to the top of the bag, a hinged bail having a pair of arms secured to the ring on a transverse median line thereof, and a pair of chains having one end connected to the ring in alignment with said arms and the opposite end connected to said bottom for limiting the

15 extension of the bag.

In testimony whereof I affix my signature.

HARRY S. WILLIAMS.
